UNITED STATES PATENT OFFICE.

DENNIS E. SIBLEY, OF CHICAGO, ILLINOIS.

MACHINE FOR SCOURING GRAIN.

SPECIFICATION forming part of Letters Patent No. 447,370, dated March 3, 1891.

Application filed October 27, 1890. Serial No. 369,446. (No model.)

To all whom it may concern:

Be it known that I, DENNIS E. SIBLEY, a citizen of the United States of America, residing at Chicago, in the county of Cook and State of Illinois, have invented certain new and useful Improvements in a Machine for Scouring Grain, of which the following is a specification, reference being had therein to the accompanying drawings and the letters of reference thereon, forming a part of this specification, in which—

Figure 1 is a perspective view of the machine having a portion of its outer case broken away to show the interior, working parts. Fig. 2 is a central vertical section of the case of the machine and an end view of rollers and endless brush-belt within the case; and Fig. 3 is an end elevation of the machine, showing the means for connecting and driving the roller brushes and for driving the belt brush.

This invention relates to certain improvements in grain-scouring machines, which improvements are fully set forth and explained in the following specification and claims.

Referring to the drawings, A represents the outer case of the machine, having at inlet-spout B near its upper end and the discharge-spouts F and G near the lower end, the spout F being provided with a suction fan-blower J for removing and discharging the dust from the grain, and the spout G serves as an outlet for the cleaned grain.

D is an endless brush-belt mounted on the drums P P, arranged one near the top of said case and one near its bottom. It is intended that the upper drum shall be driven by means of belt o to drive the said belt in the direction shown by the arrows.

S are brush-rollers arranged in a vertical train in front of the brush-belt D in such manner that their brushes intermesh with those of the brush-belt.

R are guide-rollers respectively arranged opposite the said brush-rollers against the back of the brush-belt, and are for the purpose of holding the belt against the brush-rollers. These brush-rollers are intended to be driven in the direction shown by the arrows, but at less speed than the brush-belt, so that the brush of the belt will pass rapidly between the brush of said rollers.

L are deflecting-boards arranged between each pair of brush-rollers, and are for respectively conducting the falling grain between the brush-rollers S and the brush-belt D in its descent from one brush-roller to the other. It is intended that the action of the brush of the belt and of the brush-rollers on the grain as it passes between them will scour and polish it and remove all and any objectionable substances from the grain, giving it a clean and bright appearance. A series of brush-rollers are shown as being used, so that the grain may be acted upon several times in passing through the machine.

The suction fan-blower J is used for removing the dust and refuse matter that has been taken from the grain, while the grain, being heavier, will be discharged from the spout G. The roller brushes are each provided on the outer ends of their shafts with worm-wheels W, which mesh with worms Z' on the vertical shaft J', which has its lower end stepped in the beam E, and is boxed to the outer side of the machine by means of the boxes F'. Said shaft is provided on its upper end with bevel-gear II, which meshes with bevel-gear II' on the drive-shaft J'', by means of which bevel-gears shaft J' is rotated and drives the said roller brushes. By means of regulating the size of the worms and worm-wheels the said roller brushes may be driven at different speeds if for any reason that is necessary.

When it is desired to use the machine as an oat-clipper, the brushes may be made of wire strong enough to remove the hulls and dead points from the grain.

The process for scouring the grain consists in passing the grain between the intermeshing brushes arranged to rotate toward each other but at different speeds, whereby the action of the brushes propels the grain through between them and engages it in such manner as to remove all objectionable substances therefrom and render it clean and bright in appearance as new grain.

In operation the grain is let in at the spout B and falls between the belt brush D and upper roller brush S, and the action of the two brushes upon the grain serves to remove any objectionable substance from it. A series of such roller brushes are used in connection

with the belt brush, so that the grain will be acted upon several times on its way through the machine so it will be thoroughly scoured before its discharge. Any number of roller brushes may be used, as before stated, and they may be rotated at different speeds if for any reason that is necessary or desirable; but it is always necessary to rotate the belt brush at a higher speed than the roller brushes in order to cause the brushes to act upon the grain and propel it through between them as stated.

If desired, the guide-rollers may be substituted with a back board as a backing for the belt to hold it up in contact with the brush-rollers; but the guide-rollers are found to be preferable, so far, at least, as friction is concerned.

In order to prevent grain from entering the fan-blower case, a screen V is placed across its inner end and to agitate the falling grain so as to separate it from the dust the arms Z are used on the rear inner side of the spout G, which enables the fan to remove the refuse matter in a better manner. The roller brushes S may be rotated in the opposite direction from that indicated by the arrows, if for any reason it might be found best when the machine is used on different kinds and quality of grain.

Having thus described my invention, what I claim as new, and desire to secure by Letters Patent, is as follows, to wit:

1. In the grain-scouring machine shown and described, the combination, with the case A, having the inlet-spout B and outlet-spouts F and G, of the drums P, brush-belt D, mounted

on said drums, brush-rollers S, arranged in a vertical train against the said belt brush, so their brushes will intermesh with those of said belt brush and rotate at a different speed from said belt brush, guide-rollers R for holding said belt brush in contact with said roller brushes, deflecting-boards L, screens V, and suction fan-blower J, all arranged to operate substantially as and for the purpose set forth.

2. In the grain-scouring machine shown and described, the combination of drums P, belt brush D, mounted on said drums, brush-rollers S, arranged in a vertical train against said belt brush so their brushes will intermesh with those of the roller brushes and rotate at a different speed from said belt brush, guide-rollers R for holding said brush-belt in contact with said roller brushes, deflecting-floors L, worm-wheels W, arranged on the ends of the shafts of said roller brushes, shaft J', worms Z', secured on said shaft and arranged to mesh with said worm-wheels, and bevel-gears H H' and shaft J'', all arranged to operate substantially as and for the purpose set forth.

3. In the grain-scouring machine shown and described, the combination, with the endless brush-belt B and roller brushes S, of the outlet-spout F, having the fan J, the screen V, arranged across the inner end of said spout, and spout G, having the series of arms Z arranged to extend across its inner end, substantially as and for the purpose set forth.

DENNIS E. SIBLEY.
